UNITED STATES PATENT OFFICE.

WILLIAM F. KIESEL, JR., OF ALTOONA, PENNSYLVANIA.

LOCOMOTIVE.

1,207,056.

Specification of Letters Patent.

Patented Dec. 5, 1916.

Application filed March 20, 1916. Serial No. 85,429.

To all whom it may concern:

Be it known that I, WILLIAM F. KIESEL, Jr., a citizen of the United States, and resident of Altoona, Blair county, State of Pennsylvania, have invented certain new and useful Improvements in Locomotives, of which the following is a specification.

My invention relates to railway vehicles and has particular reference to a structure for providing sufficient lateral motion of the body frame with reference to the truck and also to allow the truck to swivel.

On modern large locomotives with the increased number of drivers it is difficult to provide sufficient truck side motion with the ordinary link suspension and in order to obtain sufficient side motion on curves and also to permit swiveling of the truck I have arranged a construction in which the body frame is supported centrally of the truck by means of a rocker casting which permits relative lateral motion of the truck and body and also permits the truck to swivel.

The above and other objects and the novel features of my invention will be apparent from the following description taken in connection with the drawing in which,

Figure 1 is a longitudinal central sectional view of a truck equipped with the structure embodying my invention; Fig. 2 is a view of the same, partly in front elevation and partly in central transverse section; Figs. 3, 4 and 5 are, respectively, a plan view, a longitudinal cross sectional view and a transverse cross sectional view of the combined bolster center plate and rocker bearing; and Figs. 6, 7 and 8, are respectively, a plan view, an end view and a longitudinal sectional view of the rocker casting.

Referring to the drawing, the two-axle truck illustrated in Figs. 1 and 2 consists of the usual axles 10 and 11 and the pairs of wheels 12 and 13 mounted thereon. The truck has the usual or any preferred form of truck frame which comprises a transom 14 mounted at its ends upon the longitudinally extending springs 15 at both sides of the truck. The transom 14 has parts 141 located centrally of the truck and to these parts is secured a fulcrum casting 16. The fulcrum casting has the flanges 161 which are bolted to the parts 141 and on its upper side has a pair of spaced vertical side mem-

bers 17 which are provided with openings to receive the trunnion bolts 18.

The fulcrum casting is located centrally of the two-axle truck and forms the pivotal support for the rocker 19 which is shown in detail in Figs. 6, 7 and 8. The rocker 19 consists of a single casting which tapers toward its lower end when viewed from one side as seen in Fig. 7. The casting has two pairs of jaws at its lower end, each jaw consisting of the spaced members 20 which receive the supporting flanges 17 between them. Each of the members 20 is provided with an opening 21 which register with the openings in the members 17 whereby the rocker is pivotally supported on the trunnion bolts 18. Suitable bearings 22 are provided between the openings 21 and the bolts 18. The pairs of jaws are spaced apart a sufficient distance so that access may be had to the nuts 23 and the jaws are connected together by a suitable stiffening web 24. The upper end of the rocker casting has a head 25 which is substantially circular in outline and has a top bearing surface provided with a flat portion 26 extending diametrically across the head from one side to the other. The remaining part of the top surface of the head on opposite sides of the flat part 26 is curved or inclined away from the top flat part 26 as at 27 along the curve having its center at the pivotal center of the axis through the openings 21.

The car or locomotive body is provided with the under frame 30 and has two parallel side frame members 31 between which the body or frame supporting casting 32 is mounted. This casting is shown in detail in Figs. 3, 4 and 5 and has sides 33 by means of which it is bolted to the side frame members 31. The sides 33 are connected together by suitable stiffening ribs 34 which may have a portion of the frame resting thereon. The web 35 which connects the sides 33 is higher at its center than at the edges 36 as at 351 and the higher portion of the web 35 constitutes the bottom of a cavity 36 in the lower side of the casting. The bottom face 37 of the cavity constitutes the center plate of the body frame. Two opposite side walls of the cavity are extended downwardly to provide wings or flanges 38 disposed on opposite sides of the longitudinal center line of the truck. These flanges are connected to the sides 33 of the casting by suit-

able strengthening webs 39. At the rear the casting has an extension 40 which is provided with flanges 41 at its sides for securing the casting to another part of the under frame of the body.

- The cavity 36 of the frame supporting casting is designed to receive and mesh with the upper end of the rocker 19. Suitable liner plates 42 are secured by means of bolts 43 to the bottom of the cavity 36 for the purpose of alining the frame and also serve to compensate for wheel, journal and bearing wear. The rocker casting 19 extends into the cavity and has its bearing on the bottom side of the liner plates 42. The casting has recesses 44 in its top face to receive the heads of the bolts 43, the recesses being of sufficient length to permit the ordinary amount of swiveling of the truck. 20. This connection of the truck to the body supports the latter so that the truck may have the required side motion and also, since the cavity 36 and the head of the rocker therein are circular the truck will be allowed 25 to swivel a sufficient amount as on the ordinary center plate.

Having thus described the invention what is claimed and desired to be secured by Letters Patent is:

30. 1. In a railway vehicle the combination of a truck having a frame thereon, a body frame, and a rocker pivoted on the truck frame and swingable on its pivot transversely of the truck and body to pivotally support the body frame on the truck frame in such a manner that the truck may have side motion with respect to the body, said rocker being largest at its upper end and tapering inwardly and downwardly from its upper end to its pivot and coöperating with means on the body frame for connecting the latter to the truck frame so that the truck may swivel.
2. In a railway vehicle the combination of a two-axle truck having a transom mounted between the axles, a body frame, a rocker pivotally mounted on the transom centrally of the truck and having an upper end swingable in a plane transversely of the body and truck, a center plate forming a bearing on the under side of the body frame and having a bearing surface surrounded by a rim to form a cavity to receive the upper end of the rocker, said rocker having a flat bearing part on its upper side, the connection between the rocker and the cavity on the center plate being arranged to permit the truck to swivel.
3. In a railway vehicle, the combination of a truck, having a transom, a fulcrum casting mounted on the transom; a body frame, and a rocker pivoted on the fulcrum casting and supporting said body frame on the truck.
65. 4. In a railway vehicle, the combination

of a truck having a frame supported thereby, a fulcrum casting secured to said frame substantially centrally of the truck, a body frame, and a rocker pivoted on said fulcrum casting so as to swing transversely of the truck and having swivel supporting connection with the frame.

5. In a railway vehicle, the combination of a two-axle truck having a transom supported between the axles, a fulcrum casting mounted on the transom centrally of the truck, a body frame, a frame supporting casting secured to the body frame, and a rocker pivoted on the fulcrum casting and meshing with the frame supporting casting.

6. In a locomotive, the combination of a two-axle truck having a transom supported thereon, a fulcrum casting mounted on said transom centrally of the truck, a body frame, a rocker pivoted at its lower end on the fulcrum casting, and means whereby the body frame is supported on the top end of the rocker.

7. In a railway vehicle, the combination of a two-axle truck having a transom supported between the axles, a fulcrum casting mounted on the transom centrally of the truck, a body frame, a rocker casting pivoted at its lower end on the fulcrum casting, and means whereby the frame and upper end of the rocker are swivelly connected.

8. In a railway vehicle, the combination of a two-axle truck having a transom supported between the axles, a fulcrum casting mounted on the transom centrally of the truck, a body frame, a body supporting member secured to the body frame and having a cavity in its lower side, and a rocker casting pivoted at its lower end on the fulcrum casting and having the upper end thereof extending into the cavity of the body supporting member to carry the latter and the body and also serving to provide a swivel connection between the truck and body frame.

9. In a railway vehicle, the combination of a two-axle truck having a transom mounted between the axles, a fulcrum casting secured to the transom centrally of the truck, a body frame, a frame supporting casting secured to the body frame and having depending flanges on its lower side, and a rocker pivoted at its lower end on the fulcrum casting and having an upper end provided with a substantially circular head, said circular head having a top bearing surface upon which the frame supporting casting is mounted, the flanges on the lower side of the frame supporting casting limiting the movement of the head of the rocker, the truck being swivelly connected to the frame supporting casting by said rocker.

10. A rocker of the class described, comprising a casting having means at its lower end whereby it may be pivotally mounted on

a support and provided with a substantially circular head at its upper end having a bearing surface on the top side thereof.

11. A rocker support of the class described comprising a casting having jaws at its lower end provided with openings to receive pins for pivotally mounting the rocker on a truck and having a substantially circular head at the top end thereof provided with a bearing surface on its top side, part of said bearing surface being flat.

12. A rocker support of the class described comprising a casting tapering toward its lower end and provided with pairs of spaced jaws at the lower end having openings to receive pins whereby the rocker may be pivotally mounted on a truck, said casting having a substantially circular head at the upper end thereof provided with a bearing surface 20 on its top side having a flat portion at the

center and inclined portions on opposite sides of the flat central portion.

13. In a railway vehicle the combination of a truck, a body, a center plate mounted on the under frame of the body and having a bearing surface surrounded by a rim to form a cavity, a rocker having its lower end pivoted on the truck and having its upper end swingable in a plane transversely of the body and the truck, said rocker having a head fitting in the cavity of said center plate, the head of said rocker being provided with a central flat bearing surface and downwardly inclined surfaces on opposite sides of said flat surface, the connection between the rocker and center plate permitting the truck to swivel with respect to the body.

In testimony whereof I affix my signature.

WILLIAM F. KIESEL, Jr.
